Primary Examiner — Mehri F Bajoul

(74) Attorney, Agent, or Firm — JEEN IP LAW, LLC

(57) **CLAIM**

The ornamental design for a game device, as shown and described.

DESCRIPTION

FIG. 1 is a front, right and top perspective view of a game device, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is a front, right and top perspective view of the game device in closed state; and,

FIG. 10 is a rear, left and bottom perspective view of the game device in closed state.

The broken lines shown in the drawings illustrate portions of the game device that form no part of the claimed design.

1 Claim, 10 Drawing Sheets
